UNITED STATES PATENT OFFICE.

SAMUEL H. WITMER, OF CHICAGO, ILLINOIS.

FOLDING CABINET-BED.

SPECIFICATION forming part of Letters Patent No. 253,903, dated February 21, 1883.

Application filed December 24, 1881. (No model.)

To all whom it may concern:

Be it known that I, SAMUEL H. WITMER, a citizen of the United States of America, residing at Chicago, in the county of Cook and State 5 of Illinois, have invented certain new and useful Improvements in Folding Cabinet-Beds, of which the following is a specification.

This invention relates to those sectional bedsteads which are capable of being folded together, so as to resemble an ordinary bureau or sideboard; and my improvement consists in applying a shiftable extension to the head-section of the bed, said extension being so constructed as to preserve a vertical position when 15 the article of furniture is both open and closed, and being provided with a concealed counter-balance, in order that it may be conveniently manipulated, as hereinafter more fully described, and pointed out in the claims.

20 In the annexed drawings, Figure 1 is a perspective view of my cabinet-bedstead in its closed condition. Fig. 2 is a vertical section of the same, taken at the line 8 8 of Fig. 3, which latter illustration is a rear elevation of 25 the cabinet. Fig. 4 is a sectionized elevation of the upper portion of the cabinet, the hinged legs being inclined and the back of said cabinet slid up preparatory to opening the rear section. Fig. 5 is a perspective view of the bed 30 ready for the reception of the mattress. Fig. 6 is an elevation of the head-board of said open bed. Fig. 7 is an enlarged vertical section of said head-board.

35 My article of furniture is so constructed as to have, when closed, the appearance of an ordinary sideboard or cabinet, as seen in Fig. 1, although the proportions and style therein represented may be varied to suit the demands of the trade. This cabinet has a base or supporting-frame composed of two stout ends, A B, securely united by stretchers C D, of which stretchers the one C has hinged to it at c' the front E of the outer falling section, said front being furnished with imitation doors e and 40 drawers e'. Fastened to this front are two boards, F F', which form the side rails of the foot-section when the bed is opened, as seen in Fig. 5, said members E and F F' having secured to them a board, G, which serves as one- 45 half of the cabinet-top. Pivoted to this cabinet-top at g' are a pair of legs, Y Y', adapted

to assume a vertical position as soon as the foot-section E F F' is opened.

Hinged at d d' to the rear stretcher, D, is the head-section of the bed, said section being composed of a back, H, side rails, I I', and an end board, J, which forms the rear half of the cabinet-top, said members H I I' J being securely united together. 55

Hinged at j j' to the rear edge of this board J are legs K K', united at top and bottom by rails k k', so as to afford a secure rectangular frame capable of supporting the head-section of the bed. The back H has a vertical extension, L, provided with side wings, l l', resting 60 on the rear portion, J, of the cabinet-top; said extension being coupled to the legs K K' by boxes N N', so as to allow a slight shifting of this member L. Secured at n, near the bottom of this shiftable extension, is one end of a rope, 65 O, which, after passing around a sheave, P, fastened to the rail k, has at its lower end a counter-balance, R, traversing a weight-box, S, which latter projects from the back H of the head-section of the bed. 70

T represents a system of hooks and staples or other convenient retaining devices for securing the various members of the bed in their proper positions, both when open and closed. 75

U represents a canvas or other suitable flexible material, connecting the lower or inner ends of the members E and H, said flexible coupling serving to support the intermediate section, V, the latter being notched at v to admit guides a b, secured to the interior of the ends A B. 80

W is a turn-bar for securing the head-section of the bed in a vertical position. 85

X X' are handles applied to the rear of the sliding extension L.

When my article of furniture is in its closed condition, as shown in Figs. 1, 2, and 3, the rear or head section, H I I' J, is maintained in an erect position by the turn-bar W, while the front or foot section, E F F' G, is securely locked to said rear section by the hooks and staples T, or by catches or their equivalents. The sliding extension L rests on the rear half, J, of the cabinet-top, being steadied thereon by the wings l l'. Furthermore, when thus closed the central section, V, is suspended between the 90 ends of the base and the stretchers C D, as seen in Fig. 2. The article of furniture now 95

presents the appearance of an ordinary cabinet or sideboard, the top thereof, G J, affording considerable room for the reception of various useful or ornamented objects, &c. The cabinet 5 may, however, be readily converted into a spacious and comfortable bed by observing the following directions: The piece of furniture is first drawn a sufficient distance away from the wall of the room, and the hooks T are disengaged from their appropriate staples, after 10 which act the front or foot section, E F F' G, is turned down to a horizontal position and supported by swinging the legs Y Y' out from their respective pockets. The sliding extension L is then run up far enough on the frame K K' to enable the wings l l' to clear the top J, when said frame is swung forward, as seen 15 in Fig. 4, the counter-balance R enabling this shifting of said extension to be effected with the utmost facility. The rear or head section, H I I' J, is now turned down to a horizontal 20 position and the frame K K' is brought to a perpendicular, so as to serve as legs for supporting said section. The moment these changes 25 are effected the wings l l' rest on the upper edges of the side rails, I I', and the proper hooks being now engaged with the staples, these wings, with the extension L, and supporting-frame K K', are securely held in position. When the cabinet is thus opened, as seen 30 in Fig. 5, the flexible medium U supports the intermediate section, V, about on the same level as the bottom pieces, E and H, of the foot and head sections, respectively, thereby rendering it an easy matter for the mattress and bedding to be applied, which articles can be 35 concealed within the closed cabinet.

It is evident the cabinet can be provided with any desired arrangement of scroll-work, moldings, &c., which ornamentation can be so applied as to conceal the joints or partings of the various members. Finally, when the piece of furniture is made to imitate a sideboard, the front of the sliding extension L may have a looking-glass applied thereto.

I claim as my invention—

1. In combination with the head-section H I I' J of a folding or cabinet bedstead, the frame K K' k k', hinged thereto at j j', and carrying a shiftable extension, L, the latter being counterbalanced by a concealed weight, R, suspended from a rope, O, passing over a pulley, P, of said frame, and then secured to said extension L, substantially as herein described.

2. A folding or cabinet bedstead, consisting of the supporting-base A B C D, to which is coupled, at c c' and d d', respectively, the foot-section E F F' G, having swinging legs Y Y', and the head-section H I I' J, having hinged to it at j j' the frame K K' k k', carrying a shiftable extension, L, the latter being counterbalanced by a weight, R, suspended from a rope, O, passing over a pulley, P, of said frame, and then secured to said extension L, substantially as herein described.

In testimony whereof I affix my signature in presence of two witnesses.

SAMUEL H. WITMER.

Witnesses:

JAMES H. LAYMAN,
SAML. S. CARPENTER.
